ORNAMENTAL STITCH SEWING MACHINE

Charles Sturzlinger, Bronx, N. Y.

Application March 24, 1939, Serial No. 263,840

3 Claims. (Cl. 112—98)

This invention relates to sewing machines and more particularly to power driven, factory machines for producing ornamental embroidery and fancy stitches.

5 An object of this invention is to provide a stitch forming machine with interchangeable means whereby many varieties of designed stitches may be made in differing predetermined patterns requiring unlike lengths of stitches in transverse and lateral arrangement.

10 Another feature is in the provision of means whereby cam actuated levers control the movement of needle and goods in definite timed relation.

15 A further purpose is to provide a stitching machine with improved mechanism which actuates stitch forming means, capable of producing zig-zag, fagoting and other forms of ornamental stitches.

20 These and other important objects are accomplished by the novel construction, combination and arrangement of parts hereinafter described and illustrated in the accompanying drawings, constituting an essential component of this disclosure, and in which:

25 Figure 1 is a front elevational view, partially in section and cut away to show mechanism within the head.

Figure 2 is an elevational view showing the rear side of the machine head, the lower portion cut away to show the mechanism below the work plate.

30 Figure 3 is a transverse sectional view taken on line 3—3 of Figure 1.

35 Figure 4 is a plan view of a portion of the machine base showing the lower feed dog and its connection with the rock shaft.

Figure 5 is a transverse sectional view taken on line 5—5 of Figure 4, showing a looper-bobbin and its connections for rotating.

40 Figure 6 shows an ornamental stitch as produced by the cams indicated in Figure 8.

Figure 7 is a top plan view of the throat plate in detail.

45 Figure 8 shows a front, rear and sectional view of a double faced cam used in producing the stitch shown in Figure 6.

Referring to the drawings in greater detail, the numeral 15 designates a level base or work plate, having a strengthening rib 16 and a pair of brackets 17, integral with the base, extending downwardly providing bearings for a feed shaft 18, held from end movement by collars 19 secured to the shaft adjacent the inner faces of the brackets 17.

Another pair of brackets 20, offset from and in advance of the brackets 17 provide bearings for a tubular rock shaft 21 (see Figure 2) arranged parallel with the shaft 18. Integral with the base 15 is a hollow unit comprising an upright element 22, a horizontal arm 23 and a box-like housing 24 open at the outer end, this unit being commonly known as the machine head, and is so referred to in the following description.

5 Rotatably mounted in the arm 23 is a drive shaft 25 having on its rearwardly extending end a hand wheel 26 and belt driven pulley 27. Interiorly of the arm 23 is a flanged sprocket wheel 28, engaging a link belt 29 trained over another sprocket 30, fixed on the extending end of a drive shaft 31 rotatable within the tubular rock shaft 21. Adjustably clamped to the shaft 21 and adjacent the inner face of the lug 20, is a hubbed rocker arm 32, to the outer end of which is pivotally secured by a stud 32', a link 33 having at its upper end an enlarged head 34, cross bored and capped for engagement upon a flanged eccentric 35 secured on the drive shaft 25.

10 A triple thread worm 37 fixed on the shaft 25, meshes with a worm gear 38, firmly fixed on a cam shaft 39 extending transversely through the arm 23 and rotatable in bearings 40 and 41; a cover plate 42 prevents entrance of dust or lint into the arm and also provides additional bearing length for the shaft.

15 A plate 43 is secured to the side of the arm 23 as shown in Figure 2 in which an annular opening is provided permitting free rotation of the shaft 39. In the forward portion of the plate 43 is a pivotal stud 45 having extending ends on which front and rear links 46 and 47 are fixed to move in unison.

20 Referring to Figures 4-8 there is shown a cam 48, having a groove 49 on one side adapted to actuate the lower feed mechanism, and a groove or track 50 to produce a lateral oscillating motion to the needle bar. This cam 48 is removably held on the rear end of the shaft 39 by a key as best seen in Figure 3.

25 Referring to Figure 2, the link 46, carried on the stud 45 is provided with a cam follower operable within the groove 49 of the cam 48; on the opposite end of the stud 45, the link 47 is fixed in a manner to compel unison of movement with respect to the link 46; the lower portion of the link 47 is provided with an arcuate slot 51 for adjustment.

30 Pivottally mounted at the upper portion of the head 24 is a needle guide bar 52 provided with aligned bearing elements 53 in which a needle 55

- bar 54 is slidably mounted; near the lower end of the guide bar are opposed laterally extending lugs 55—56, the former having a curved slot 57 in which is a shouldered retaining screw 58; the lug 56 has a rigid pin 59 fixed therein.
- Transmission of vibratory movement from the link 47 to the needle guide bar 52 is provided by a connecting link 60, having adjustable bearing ends 61—62 adapted for connection on the pin 59 and a stud 63, adjustable in the slot 51 of the link 47.
- Bolted to the rear of the upright element 22 is an angle plate 64, to which a lever 65 is pivotally engaged at its rear end by a shouldered thumb screw 66 and at its reduced front end, at a point in vertical registration with the cam axis 39, is a fixed cam follower 67, operative in the groove 50.
- Midway in the length of the lever is a slot 68 for adjustment of a forked yoke 69 having an upwardly extending lug 70, provided with means for threadably engaging a shouldered clamp screw 71 for lateral adjustment between the yoke 69 and the lever 65.
- A knurled headed adjusting screw 72 is freely operable in the forked ends of the yoke and threadably engages an enlarged head 73 at the upper end of a bent lever 74, passing through an aperture 75 in the upright 22, then downwardly through the base 15 and terminating in a curved end formed at an angle and pivotally engaged by shoulder screw 74' with a lever 76 clamped to the feed shaft 18.
- Another lever 77, adjustably clamped to the hollow shaft 21, is provided with a fixed pin 78 engageable in a swivel block 79, slideable within a forked element of a feed dog 80 having an upward extending toothed element 81 passing through the throat plate 82 and adapted to move the fabric in transverse reciprocating directions. The rear portion of the feed dog 80 has at its rear end a fixed pin 83, rotatably engaging the end of a lever arm 84 adjustably clamped to the rock shaft 18.
- The front portion of the cloth feed dog 80 is provided with extending hub elements 85—86 (see Figure 1) and is mounted between bearings 87—88 of the feed dog carrier 84, and is pivotally held by a shaft 89 passing therethrough. The feed dog carrier has a bore 90 fixed to the rocker shaft 18.
- A looper-bobbin 100, of conventional type, is initially operated by a pair of bevel gears 101—102, the gear 102 being fixed on the end of the drive shaft 31 to mesh with the gear 101, which is fixed on a shaft 103, revolvable in a bearing 104 extending transversely through a lug 105 secured to the base 15. The looper 100 is removably held on the inner end of the shaft 103 and adjacent the hub of the bevel gear 101.
- The throat plate 82, best shown in Figure 7, presents a flat plate adapted to fit a recess formed on the top face of the base 15 and there removably held by screws 106 engaging threaded holes 107 of the base 15.
- Pierced through the plate 82 are openings 108—109 receptive of the feed dogs 81 movable in the openings; a central elongated slot 110 permits movement of the needle 111 longitudinally therein, also an upwardly extending guide pin 112.
- The needle bar 54 receives initial motion from a balanced eccentric 113 rigidly secured to the drive shaft 25, which, with associated parts connecting the eccentric and needle bar in the well

known conventional manner, provides a vertical reciprocating motion to the needle bar.

A presser foot bar 114 is manually operated by a handle 115 which raises and lowers the bar when required. Secured to the lower end of the bar 114 is a compensating presser foot 116 consisting of a pair of opposed presser elements 117—118 adapted for vertical reciprocating movement, independently of each other; a slotted plate 119 retains the presser elements in slidable contact with the presser foot 116 and pins 120, working in slots in the plate 119 assist in keeping the presser elements in level normal position; upward movement of either presser element is limited by contact of the top of the plate 119 with a stop collar 121 fixed to the presser foot 116.

The operation, the machine is hingedly mounted on a work table having means therewith for conveying rotary motion through a belt trained over the drive pulley 27 fixed to a shaft 25 passing longitudinally through the arm of the machine in a manner commonly employed.

Transversely of the driven shaft 25 is a short shaft 39, carrying a worm gear 38 in mesh with a worm 37; removably held on shaft 39 is a cam 48 having on opposite faces grooves differing in outlines thereby producing different stitch designs.

Below the base 15 are a tubular shaft 21 and a solid member 31 on which is mounted a sprocket 38 aligning with another sprocket 28 fixed on the shaft 25 and a link belt 29 is trained over the sprockets.

An eccentric 35 fixed on the shaft 25 carries an arm 33, connected to a lever 32 adjustably clamped to the tubular shaft, thereby imparting a rocking motion to the shaft 21, when the shaft 25 is rotated. At the opposite end of shaft 21 is adjustably clamped another lever 77 having at its end a pin 78 engaging a block 79 slideable in a forked element of a feed dog 80; thus it will be seen that as the shaft 21 is rocked, or partially rotated, the toothed feed dog 80, will be raised and lowered in timed relation to the needle bar 54.

Below the plate 15 is another rock shaft 18, motion being imparted to it by means of interconnected elements, as the rocker arm 76, adjustably clamped to the rock shaft 18; an out-reaching link 74 extends upwardly and then outwardly through the machine frame and has a head 73 receptive of a knurled headed screw 72 for fine transverse adjustment of the feed dog 81, and a yoke or forked member 69 carries the adjusting screw.

A cam follower link 65, pivoted at one end to a bracket 64, has a cam following roll 67 engaged in a groove 50 of the double cam 48, the link 65 being adjustably clamped to an upwardly extending element 70 of the yoke 69, providing a complete, positive means for adjustably controlling the rocking movement of the shaft 18, on the front end of which is secured a carrying head element 84, having bearing means adapted to engage a pin 89, passing through hub elements 85—86 formed at the end of feed dog 80; it will now be seen that as the shaft 18 is rocked, the feed dog will be moved forward and backward by the action of the head 84 which is fixed to the rock shaft 18.

A vibratory, or laterally reciprocating motion of the needle 111 is initially attained by means of the cam 48 having a groove 49 formed on its face; a cam follower link 46 pivotally operating through a plate 43 is rigidly connected to a slotted link 47; a needle vibratory bar 52 is pivoted at its 75

upper end to the machine head 24. The lower end of bar 52 has lugs 55—56, the slotted lug 55 being held against the machine head 24 by a shoulder screw 58, the other lug 56 being provided with a stud 59 adapted to pivotally retain one end of a connecting link 60, the opposite end having means for pivotal engagement with a stud 63 secured adjustably in a slot 51 of the link 47.

It will be seen that as the cam 48 is rotated, the needle will be moved sidewise in varying degrees of movement as the needle passes through the cloth, and below the bed plate of the machine, and the throat plate 82, as in Figure 7.

The presser foot 116 secured to the bar 114 is provided with a pair of compensating rocker elements 117—118 slidably mounted on the flat lower portion of the foot 116; these sliding members are controlled by the cam-like element 119 which keeps them in a normal horizontal plane. The purpose of these independently movable rocker elements is to compensate for inequality in thickness of materials being fed under the presser foot.

In the formation of ornamental stitches, it is necessary that a combination bobbin and loop-taker be employed; heretofore a conventional type of bobbin holder has been used. Referring to Figures 2 and 5, a bobbin holder is shown connected to a bevel gear 101, fixed to a shaft 103 rotatable in a bearing 104 adjustably held in a lug 105 secured to the under side of the base plate 15 and in mesh with a mating bevel gear 102, fixed on the end of the constant drive shaft 31; it will be understood that gears, other than of equal proportions, may be required to produce certain forms of ornamental stitches. It will also be apparent that cams greatly varying in groove outlines must be employed to meet conditions involved when a change in stitch pattern is made.

Many different modifications of this invention may be made without departing from the spirit and scope thereof, and it is to be understood that

it is not desired to limit the specific embodiments thereof except as defined in the appended claims.

Having thus described the invention, what is claimed as new and sought to secure by Letters Patent is:

1. In a sewing machine for producing embroidery stitches, in combination with the needle, feed and shuttle operating means, a double faced cam, one of its faces controlling the action of said needle and the other face controlling the action of said feed, a lever actuated by the latter named face, a yoke adjustable on said lever, and screw actuated means carried by said yoke for minutely adjusting the action of said feed and means for rotating said cam.

2. In a sewing machine for producing embroidery stitches, in combination with the needle, feed and shuttle operating means, a cam, means actuated by the machine to rotate said cam, a lever actuated by said cam, a yoke adjustable horizontally on said lever, an adjusting screw revoluble in said yoke, a second lever mounted on said screw, a spindle operatively connected to said feed, and connections to said spindle actuated by the last named lever.

3. In a sewing machine for producing ornamental stitches including a reciprocable needle and a movable feed, a double faced cam interchangeably driven by the machine, one of said faces connected to oscillate said needle bar in a given path, the other cam face to actuate said feed, a lever directly driven by the last named cam face, said lever being pivoted on a horizontal axis remote from the cam and having a slot midway its length, a yoke adjustable in the slot, said yoke having spaced depending arms, a manually operable adjusting screw mounted in said arms, a spindle to actuate said feed, and a link to actuate said spindle, said link being connected to said screw whereby it may be adjusted.

CHARLES STURZLINGER.
